DESIGN FOR A DRESS

David Rosenthal, New York, N. Y.

Application September 2, 1936, Serial No. 64,681

Term of patent 3½ years

To all whom it may concern:

Be it known that I, David Rosenthal, a citizen of the United States of America, residing in Manhattan, county of New York, and State of New York, have invented a new, original, and ornamental Design for a Dress, of which the following is a specification, reference being had to the accompanying drawing, forming part thereof, wherein,

The design is characterized by novelty lattice work on the shoulder and bottom edge portion of the skirt, in combination with the dress, as shown.

I claim:

The ornamental design for a dress, substantially as shown, and described.

DAVID ROSENTHAL.
